UNITED STATES PATENT OFFICE.

THOMAS FINIGAN, OF PATERSON, NEW JERSEY.

MACHINE FOR CLEANING VEGETABLE FIBER.

SPECIFICATION forming part of Letters Patent No. 746,056, dated December 8, 1903.

Application filed October 16, 1902. Serial No. 127,530. (No model.)

To all whom it may concern:

Be it known that I, THOMAS FINIGAN, a citizen of the United States, residing at Paterson, in the county of Passaic and State of New Jersey, have invented certain new and useful Improvements in Machines for Cleaning Vegetable Fiber, of which the following is a specification, reference being had therein to the accompanying drawings.

10 In the drawings, Figure 1 is a front elevation of my fiber-cleaning machine, showing where the leaf enters. Fig. 2 is a side elevation of the opposite side of the machine. Fig. 3 is a top plan view of the machine. Fig. 4 is a vertical sectional view of a portion of the shoe, showing the stationary guide-race secured thereto and inclined lip of the guide entering a slot in the grip-wheel between two bands of teeth constituting the gripping device. Fig. 5 is a vertical side elevation in section, showing the relative position of scutching-wheel, gripping device, and guide-shoe with a triangular deflected portion. Fig. 6 is a sectional view of an auxiliary cleaning wheel and shoe and fiber-gripping device. Figs. 7, 8 are different views of knife-blades or guillotine and eccentric that operates the blades for cutting fiber off close to the butt. Fig. 9 is an illustration of the leaf as it comes 30 from my machine after being operated upon, with the exception that the butt 2 has not in this figure been cut from the fiber 1.

This invention relates, generally speaking, to machines which are intended for removing the pulp from the fibers of plants of various kinds for the purpose of separating the cellular tissue and other matter from the fibers and cleaning the said fibers. Many complicated machines have been constructed for that purpose which because of their numerous parts have been both expensive and difficult to transport from place to place as well as cumbersome. They have also required considerable power to drive them and have 40 embodied in their construction systems of gears and chains that required much attention on the part of the operator and have required more than one operation to remove the cellular tissue and other substances from 50 the fibers in the plant or leaf.

The object of my invention is to provide a more simple and inexpensive machine em-

bodying various improvements which will obviate the necessity of employing chains and complicated systems of gearing and which will accomplish the purpose in one operation. 55

My machine consists of a large cleaning-wheel B, mounted in a frame A A', driven by suitable power and coacting with a shoe C, which is placed in close contact with blades B', that are secured to the periphery of the wheel, between which shoe and the wheel the leaf is passed by the action of a rotary grip-wheel D on a stationary guide-race H, which forms part of the shoe C. The shoe is so 60 formed on its face that the blades B' come first into contact with the point of the leaf and as the leaf passes along the face of the shoe each succeeding blade strikes the leaf higher and higher until the leaf reaches that 65 part of the shoe where a true circle is formed to align with the disk of the wheel B, whereupon the blades of the revolving wheel B scrape successively the whole leaf, except the extreme butt or portion, which is held in the 70 grip of the wheel D and the stationary race H. 75

The leaf is fed in by the butt 2 between the teeth D' of the wheel D and the inclined mouth or entrance to the race H at the point indicated by the arrow at the top of Fig. 3, 80 where the said teeth engage the upper side of the leaf and carry it along the stationary race H, which is provided with a lip or shoulder H', that extends into an annular groove D' in the toothed surface of the wheel D, until it reaches a small vertical wheel K' and friction hub or roller K, which is driven by friction from the toothed wheel D, where it is bent down and caused to conform to and enter the entrance to the shoe C, which is open 85 to receive it on its upper part nearly two-thirds of its width at its upper portion; but not at the point or lower part where the leaf is first caught and acted upon by the blades B' of the wheel B. 90

The lip H' on the stationary race H is arranged to rise up gradually to interlock in the annular groove formed in the under side of the toothed wheel D and obtains its highest point where the whole surface of the leaf 95 is being scraped by the blades of the wheel B. It is thus obvious that the whole of the leaf is operated upon without drawing out or damaging the short fibers of the leaf. 100

The flutes in the face of the shoe are intended to save a great amount of labor in cleaning the thick part or butt, as a part of the fibrous leaf will sink into the grooves C³ 5 and then rise out and over the ribs C² and be scraped, thus tending to stop the rolling motion of the fibers that are being scraped and prevent the curl which is produced in the fibers when dried by such a rolling motion.

10 By the time the whole leaf has been acted upon between the wheel B and the shoe C a bunch of cleaned fibers 1, depending from the short butt 2, makes its exit, and the fibers are caught by rope R at a point where the toothed 15 wheel D and the race H let the butt 2 go, that being the point where the race H ends, and an idle sheave in contact with the rope R causes the fibers to be drawn through or between another small cleaning-wheel F and 20 a shoe F', which scrapes off the pulp adhering to the butt 2, where it was previously held in the grip. After leaving said last-mentioned small wheel and shoe the fibers, entirely cleaned, are conveyed to a point where the 25 rope R and idle sheave part company, as indicated by arrow and are delivered and caught by the hand or in any suitable manner, as desired.

As only a small portion of the butt of the 30 leaf is required to be held in the grip—namely, about one inch—my machine may be simplified, if desired, by dispensing with the small clean wheel and shoe, and instead of cleaning the butt of the leaf it and the fibers depending therefrom may be conveyed from the cleaning-wheel D to a knife (shown in Fig. 8) which 35 severs the short butt D from the cleaned fiber 1. Said knife is driven by an eccentric on the shaft driving the toothed feed-wheel 40 and is located in close proximity to the rim of the feed-wheel, so that the fiber will be cut off close to the grip, leaving unutilized only the small butt of the leaf.

Fig. 8 shows the eccentric L on the horizontal shaft T and its strip L', secured by pivot L² to the rocking arm M, which works on the pivot M' and is provided with the upper blade m', which, with the lower fixed blade m, secured by screws m² or in any other suitable 50 manner, constitute the knife or guillotine.

The horizontal shaft T operates the worm-wheels and is driven by the spiral gear-wheels T⁴ and T⁵, the worm T⁴ operating the wheel E and the worm T⁵ operating the worm-wheel T³.

55 W is the vertical shaft of the wheel D and is supported in bearings W' and W², secured to the lower and upper portion of the machine-frame A and A', respectively.

The triangular deflected portion C' of the 60 surface of the shoe C is indicated by the angles a b c, formed by said deflection. If the shoe C did not have what I call the "triangular" portion of its surface deflected, it would consist of an oblong metallic plate curved, so 65 that its upper surface would be concentric or almost concentric with the circumference of the scutching-wheel, and the knives or blades

across the perimeter of the scutching-wheel in the revolution of the wheel would sweep over the said shoe from the top to the bottom 70 thereof and would begin to operate at the top of the shoe on any fibrous plant or leaf which would be inserted between the shoe and the wheel. This result I wish to avoid and I do so by bending the upper left-hand corner of 75 the oblong plate on the line a b, thus deflecting the triangular portion a b c, so that the knives in passing the curved shoe will begin to operate on the fibrous plant or leaf which is passing between the shoe and the wheel at 80 the lower portion of the leaf or below the angle b, the fibrous plant or leaf being carried over the shoe from left to right (see Fig. 4) each succeeding knife will operate thereon at 85 a higher point as the plant or leaf passes from the deflected triangular portion beyond the diagonal line a b or terminal limit of said deflected portion. This obviates the collection of pulp, which would accumulate if the knives began to operate upon the upper portion of 90 the plant or leaf. The shoe is secured to the frame and adjusted by the bolts f and f' and adjusted nut and screw C⁴ and C⁵, which may be manipulated to fix the shoe in the desired position with relation to the wheel B and the 95 blades thereon. Power may be communicated to the shaft of the scutching-wheel B through belting and the usual set of fast and loose pulleys B² or in any other well-known or suitable manner.

Owing to the great speed of the revolution of the scutching-wheel the bagasse scraped from the fibers would fly, and to prevent this I provide the cover or fender B³. A pressure-roller N is forced down by the spiral 105 spring S to tighten the grip of the wheel D over the stationary race H at the working portion of the grip. The race H is secured to the shoe C by the bolts H⁵. (See Fig. 7.)

The endless rope R passes around the 110 sheaves n' and n² and in contact with the sheave n, and said sheave n² is operated from the horizontal shaft T.

It is obvious that many modifications may be made in the construction of my machine 115 without departing from the broad principles and the essential spirit of my invention.

With this description of my invention what I claim as new, and desire to secure by Letters Patent, is—

1. In a fiber-cleaning machine, the combination of a scraping-wheel having blades mounted upon the periphery thereof, with a cleaning-shoe constructed so as to present a concave surface narrow at the top and gradually widening toward the bottom and concentric with said wheel, substantially as set forth.

2. In a fiber-cleaning machine, a scutching-wheel, having blades mounted upon its periphery and a shoe having a concave surface concentric with said wheel and downwardly increasing in width, in combination with a horizontal wheel or disk having un-

derneath serrations or teeth and a groove, a stationary guide having a projection on its upper surface adapted to enter said groove, means for guiding a leaf laterally between

5 the shoe and the scutching-wheel and means for giving a downward pressure to said horizontal wheel or disk, substantially as set forth.

3. In a fiber-cleaning machine, a leaf-conveying device consisting of an upper moving disk and a lower stationary smooth race or guide upon which the fibrous leaf may slide and yet be firmly gripped, said disk on its under side at its periphery having narrow

15 annular bands of serrations or teeth, and a groove or recess sunk between said bands of teeth, the guide or race being provided with a raised lip partly entering said groove for the purposes of interlocking the end of the

20 leaf in said teeth, groove and lip, substantially as specified.

4. In a fiber-cleaning machine, the combination of a cleaning and scraping wheel provided with straight blades, with a revolving

25 horizontal wheel, a groove formed in the under side of said wheel and a series of serrations or teeth located on each side of said groove, and a cleaning-shoe having a race-way on its upper edge formed to interlock

30 and operate in said groove, substantially as set forth.

5. In a fiber-cleaning machine, the frame, and a scutching-wheel, in combination with a cleaning-shoe having a concave surface

35 which is narrow at its upper edge and gradually increases in width from the top until it

is the full width of the shoe and aligns with the periphery of said scutching-wheel, a triangular space or portion on the face of said

40 shoe situated to one side of a suppositionary

line drawn from a point a short distance from one side of the upper edge of the shoe to a point on the other side and near the lower edge of the shoe being bent or curved out of

45 alinement with said scutching-wheel to permit a leaf to readily pass between said wheel and said shoe, and to permit the leaf to be struck or scraped progressively, at points along the said suppositionary line, as the leaf

50 crosses said line in passing over the surface of the shoe, substantially as set forth.

6. A cleaning-shoe for a fiber-cleaning machine, having a concave surface crossing-diagonally from one side to the other and adapted to be located concentrically with re-

55 lation to the periphery of a cleaning or scrap-

ing wheel, and having a portion bent away at an angle from said concave surface, in combination with a cleaning and scraping wheel, substantially as set forth.

60

7. In a fiber-cleaning machine, a scutching-wheel, in combination with a curved cleaning-shoe parts of the face of which are formed of different radii alternately, and forming grooves, on said face, and feeding means for

65

the purpose set forth.

70

8. The combination of the scutching-wheel and a fixed shoe having a portion of its upper surface deflected out of parallel, and not concentric, with the periphery of the scutching-

75 wheel, substantially as set forth.

9. The combination of the scutching-wheel,

provided with blades secured to the periphery

thereof and parallel with its axis, of a fixed

shoe having a portion of its upper surface de-

flected out of parallel, and not concentric,

with the periphery of the scutching-wheel,

substantially as set forth.

10. The combination of the scutching-wheel, provided with straight-edged blades secured

80

to the periphery thereof and parallel with its

axis, with a fixed shoe having a triangular

portion of its surface deflected out of parallel,

and not concentric, with the periphery of the

scutching-wheel, and means for conveying

85

a fibrous leaf between said scutching-wheel

and shoe so that the lower end or point of the

leaf is first acted upon by the blades of the

scutching-wheel as the leaf is conveyed be-

tween said wheel and shoe, substantially as

90

set forth:

11. In a fiber-cleaning machine, the combination with the scutching-wheel having blades on its periphery parallel with its axis, of a shoe having a triangular portion of its

95

surface deflected, a grip device consisting of

a stationary guide-race secured to and form-

ing a part of the guide or shoe and a hori-

zontal grip-wheel provided with an annular

slot having a band of serrations or teeth on

100

each side thereof, a projection on said sta-

tionary guide-race adapted to enter said slot

to interlock therewith and firmly grip the

butt-end of a fibrous leaf, and a means for

cutting the fiber off close to the portion

105

gripped, substantially as set forth.

In testimony whereof I affix my signature in presence of witnesses.

THOMAS FINIGAN.
